UNITED STATES PATENT OFFICE.

ISAAC SCHAFRAN, OF NEW YORK, N. Y., ASSIGNOR OF ONE-HALF TO LOUIS BRUGER,
OF MONTREAL, QUEBEC, CANADA.

DUPLEX AIR ROTOR.

Application filed May 15, 1922, Serial No. 561,195. Renewed November 28, 1925.

To all whom it may concern:

Be it known that I, ISAAC SCHAFRAN, a citizen of Rumania, residing at 301 Madison Avenue, New York city, in the State of New York, in the United States of America, have invented certain new and useful Improvements in Duplex Air Rotors; and I do hereby declare that the following is a full, clear, and exact description of the invention, such 10 as will enable others skilled in the art to which it appertains to make and use the same.

This invention relates to a duplex air rotor, which is illustrative of a novel means 15 for using all the available energy delivered by an aerial propeller.

It is well known in aeronautics that a propeller creates two forces in opposite directions, namely, the thrust and the back stream. 20 The thrust is the forward movement and is utilized in driving an aeroplane, while the back stream, which is incidental to the thrust, is directed rearwardly. This back stream has as yet not been utilized, and the 25 object of this invention resides in the means for utilizing the back stream in conjunction with the thrust.

In the accompanying drawings and specification, the principle of the invention is 30 shown as applied to a generator. A pair of shafts are employed, to one of which a propeller is fixed. The thrust of the propeller results in rotation of the shaft. The other shaft carries a turbine disposed within the 35 back stream of the propeller and adapted to utilize the same whereby the turbine is rotated. These two movements, which are in opposite directions, are available for the rotation of a magnetic field and an armature 40 therein, these latter elements being mounted respectively on the two shafts.

In the accompanying drawings in which an illustrative form of generator is shown:

Figure 1 is a front view of the device;

45 Figure 2 is a similar fragmentary view in section;

Figure 3 is a section on the line 3—3 of Figure 1;

Figure 4 is a detail of one of the yokes;

50 Figure 5 is a section on the line 5—5 of Figure 1;

Figure 6 is a section on the line 6—6 of Figure 1;

Figure 7 is a section on the line 7—7 of Figure 1; and,

Figure 8 is a section on the line 8—8 of Figure 1, showing the means of supplying current to the propeller motors.

Referring to the drawings by reference characters throughout the various views, the 60 numeral 1 indicates a pair of journal bearings consisting of pillows 2 and caps 3. A shaft 4 is supported at its ends for rotation in the bearings according to any usual or desired manner. A turbine 6 is keyed to 65 this shaft preferably at the intermediate portion thereof for a purpose later to be described. At each side of the turbine is a hollow shaft 7 carrying a wheel 8 at one end and a drum 9 at the other. These hollow 70 shafts surround and are concentric with the first named shaft 4, and are supported in this position by means of the journal bearings 10. The respective wheels 8 are connected to one another by means of the yokes 75 11 at any desired number of places along their circumferences. The saddles 12 of the yokes are inclined towards the turbine, and each saddle supports a motor 13 to the rotor or shaft of which is keyed a propeller 14. 80 These propellers are of the aerial type, and are capable of driving themselves forward and at the same time delivering a back stream. The size of these propellers is governed entirely by conditions, and in all cases 85 they should be inclined toward the turbine in such a manner as to deliver their back stream thereto with the utmost efficiency. This condition is governed largely by the inclination of the saddles 12. 90

Each drum 9 has secured to its inner surface a plurality of windings or coils 15 which carry a current and thus constitute a magnetic field suitable for a generator. It is to be noted here that these poles, being 95 immovable relatively to the wheels 8, are rotated with them, namely, in unison with the thrust of the propellers 14. The outer ends of the inner shaft 4, which protrude beyond the hollow shaft 7, each carry an armature 100 16 disposed within one of the magnetic fields and adapted to cooperate therewith. The armature illustrated in this instance is of the spider type, having spiders 17 and a winding 18, as clearly shown in Figure 6. 105

For the purpose of supplying current to the motors 13, contact rings 19 are mounted at the side of one of the wheels 8, and current is conducted to these rings through the brushes 20. Conductors 21 form a circuit 110

from the rings through the motors. The commutator 22 of the generator is engaged by commutator brushes 23 through which the current flows to the collector rings 24 mounted on the outside of the drums 9. These rings are insulated from the drum by means of a band 25. The current is conducted away from the collector rings through the brushes 26 in a well known manner. A similar set of slip rings 27 are likewise mounted on the drum and insulated therefrom by means of the band 25. These rings are in circuit with the field coils for supplying current thereto, which current is delivered to the rings through the brushes 28.

The operation of the device is as follows: A current having been supplied to the motors 13 in any usual or well known manner, the aerial propellers 14 are set in rotation, whereupon the yokes 11 and wheels 8 are driven in the direction of the arrow *a* in Figure 5. As already pointed out, the drums 9 and the magnetic fields contained therein are rotated in the same direction. The back stream of these propellers is driven against the turbine 6, the blades 6' of which are so arranged with respect to the propellers as to receive the full force of the back stream, whereupon the turbine is driven in the direction of the arrow *b* in Figure 5. This movement is directly imparted to the shaft 4, since the turbine is keyed thereto, and as a consequence the spider armature 17 is simultaneously rotated in the same direction. The final result is the opposite movements of the poles 15 and the armature 17 and the consequent production of an electric current.

It will be understood that the generator described and illustrated may be modified in several ways in order to make it better suitable for particular uses for which it is destined without departing from the spirit of the invention. For instance, the nature of the various windings and the manner of winding them on the respective shafts may be altered to meet required conditions. The invention is to be understood, however, as a means for utilizing all the available power from a propeller, as indicated by the appended claims.

Having thus fully described the inven-

tion, what I claim as new and desire to protect by Letters Patent is:—

55

1. A motive mechanism comprising a movable body, a propeller rotatably supported by said body and adapted to actuate the same, a second movable body disposed in and adapted to be moved by the back stream of the said propeller, and means for combining the energy delivered by the two bodies.

60

2. A motive mechanism comprising a pair of shafts, one within the other and supported for independent rotation, a propeller supported on one of said shafts and adapted to rotate the same, and a turbine keyed to the other shaft, said turbine being disposed in the back stream of said propeller.

65

3. A motive mechanism comprising a pair of shafts, one within the other and supported for independent rotation, a propeller supported on one of said shafts and adapted to rotate the same, a turbine keyed to the other shaft, said turbine being disposed in the back stream of said propeller, a field frame carried by one of said shafts, a magnetic field arranged within said frame, and an armature carried by the other shaft and disposed within the field.

70

4. A motive mechanism comprising a pair of shafts, one within the other and supported for independent rotation, a propeller supported on one of said shafts and adapted to rotate the same, a turbine keyed to the other shaft, said turbine being disposed in the back stream of said propeller, a drum carried by one of said shafts, a magnetic field arranged within said drum, an armature carried by the other shaft and disposed within the field.

75

5. A motive mechanism comprising a pair of shafts, one within the other, the inner shaft extending beyond the outer one, a propeller supported on the outer shaft and adapted to rotate the same, a turbine keyed to the inner shaft and disposed in the back stream of the propeller, a drum fixed to the end of the outer shaft, a magnetic field arranged within said drum, and an armature fixed to the protruding end of the inner shaft and within the field.

80

In witness whereof I have hereunto set my hand.

ISAAC SCHAFRAN.
